UNITED STATES PATENT OFFICE.

WILLIAM C. HORNER, OF INDIANAPOLIS, INDIANA, ASSIGNOR TO
CHARLES P. McDougall, OF INDIANAPOLIS, INDIANA.

SLIDING BIN.

No. 823,784.

Specification of Letters Patent.

Patented June 19, 1906.

Application filed October 7, 1905. Serial No. 281,853.

To all whom it may concern:

Be it known that I, WILLIAM C. HORNER, a citizen of the United States, residing at Indianapolis, in the county of Marion and State of Indiana, have invented certain new and useful Improvements in Sliding Bins, of which the following is a specification.

The object of my invention is to produce a simple yet efficient sliding-bin structure especially designed for kitchen-cabinets in which the outer end of the bin will be projected downward as the bin is drawn from the casing, the mechanism being such that the bin cannot become accidentally disconnected from its supporting means, but also such that it may be very easily disconnected when in one position, so as to be withdrawn entirely from the inclosing casing to facilitate cleaning.

The accompanying drawings illustrate my invention.

Figure 1 is a central vertical section of an embodiment of my invention, the bin being closed. Fig. 2 is a similar view with the bin open. Fig. 3 is a detail, on a larger scale, on line 3 3 of Fig. 2; and Fig. 4, a perspective of the hanger.

In the drawings, 10 indicates a suitable inclosing casing having a compartment 11, within which the sliding bin 12 is mounted. The bin 12 is slidably supported at its outer lower corner upon a roller or wheels 14, while at each inner lower corner it carries a plate 15, provided with a pin 16, which lies substantially at right angles to the direction of desired motion of the bin and is adapted to be received by the adjacent hooked lower end 17 of a hanger 18, pivoted at its upper end at 19 in the compartment 11.

In order to prevent accidental disassociation of the pins 16 and hooks 17, each plate 15 carries a guard-flange 15', which is so arranged with relation to pin 16 that when the bin is in closed position, as shown in Fig. 4, and the hanger 18 is in its rearmost and normal position the inner end of the bin 12 may be tilted up, as shown in dotted lines in Fig. 2, the roller 14 serving as a fulcrum, and the pins 16 withdrawn from the hooks 17; but the flange 15' is projected to such a point beneath the pin 16 that so soon as the bin 12 is drawn bodily forward over roller 14 and pins 16 thereby draw the lower end of the hanger 18 forward and upward each flange 15' will swing beneath the adjacent hooked end 17 of

the hanger 18, as shown in full lines in Fig. 2, and thus prevent the withdrawal of the pins 16 from their associated hooks 17.

It will be noticed that the point of possible separation of the pins from the hangers is 60 that in which the hangers occupy their normal position and that the movement of the bin to the position shown in dotted lines in Fig. 2 does not distribute the hanger so that it is possible to reassociate the pins 16 and 65 the hanger by a very simple movement without difficulty and without the necessity of the operator seeing the parts.

Under normal conditions when the bin 12 is pulled outward it will slide freely on the roller 14, and owing to the connection between the bin and the hanger 18 the inner end of the bin will be thrown upward as it is drawn forward, and the outer end of the bin will therefore be tilted down as it comes to 75 its open position, the forward movement of the bin being limited either by engagement of the inner upper corner of the bin with the casing or by a sufficient movement to bring the pins 16 into alinement with the roller 14 80 and pivot 19.

I claim as my invention—

1. The combination, with a suitable supporting structure, of a bin mounted therein and slidably supported near its lower corner, 85 a swinging link pivoted in the supporting structure, and a separable connection between said link and the inner end of the bin, said connection being separable by an unusual movement of the bin relative to the 90 link.

2. The combination, with a suitable supporting structure, of a bin mounted therein and slidably supported near its lower corner, 95 a swinging link pivoted in the supporting structure, a separable connection between said link and the inner end of the bin, and interengaging portions between said bin and link serving to prevent separation except in one position of the bin relative to the link. 100

3. The combination, with a suitable supporting structure, of a bin slidably mounted therein, a link pivotally mounted in said structure, a separable pin-and-hook connection between said link and the inner end of 105 the bin, and means for preventing separation of said pin-and-hook connection except in one position.

4. The combination, with a suitable supporting structure, of a bin slidably mounted 110

therein, a fitting attached to the inner end of said bin and provided with a pin 16 partially guarded by a guard 15', and a pivoted link mounted within the structure and provided 5 with a hooked end adapted to pass between the pin and guard, substantially as and for the purpose set forth.

In witness whereof I have hereunto set my hand and seal, at Indianapolis, Indiana, this 27th day of September, A. D. 1905.

WILLIAM C. HORNER. [L.S.]
